UNITED STATES PATENT OFFICE

JULIUS PAUL, OF DULUTH, MINNESOTA, ASSIGNOR OF FIFTY PER CENT TO RICHARD M. SELLWOOD, OF DULUTH, MINNESOTA

BRAKE

Application filed January 21, 1928. Serial No. 248,453.

This invention relates to shaft braking mechanisms and has special reference to that form of device known as hydraulic brakes, the preferred form of liquid used in this embodiment of the invention being oil.

The principal object sought is that of efficiency, while other objects such as simplicity and durability are also accomplished.

Still other objects and advantages of the invention will appear in the further description thereof.

Referring now to the accompanying drawing forming part of this application and wherein like reference characters indicate like parts:

Figure 1 is a vertical central section through one of the braking devices as installed upon a shaft such as for example the drive shaft of an automobile;

20 Figure 2 is an elevation of the brake drum head taken on the line 2—2, Figure 1, assuming the drum and head as being separated;

Figure 3 is an elevation of the back of the valve controlling rocker head; and

25 Figure 4 is an elevation of the pump rotor showing the arrangement of cylinders therein.

1 represents the shaft to which the brake mechanism is applied and which as before inferred may be the drive shaft of an automobile or otherwise as desired. Upon this shaft is mounted the non-rotatable main body portion 2 of the brake housing or drum, and also the drum head 3, they being united as by suitable holding bolts 4 thereabouts and supported in any desired manner externally of the shaft. Within the drum and keyed to the shaft is mounted the pump rotor 5, it being concentric with the shaft, while the 30 brake drum is somewhat eccentric with the shaft for purposes hereinafter described.

Intermediate of the rotor 5 and the concavo-convex end of the drum 2 is mounted the valve controlling rocker head 6, and intermediate of it and the rotor is installed a suitable thrust bearing of any desired construction, preferably comprising the two spaced disc-like ball raceways 7 and 8, with balls 9 therebetween so as to reduce as much as possible the friction intermediate of the pistons 23 and

24 carried by the rotor and the rocker head 6. This head is provided with the finger-like extension 11 upwardly therefrom which impinges the valve controlling plunger 12, and is also provided with transverse gudgeons 13, 55 one upon either side thereof, which are journaled in any desired manner within the opposite walls of the drum 2, so that the head is free to rock upon said gudgeons in its manipulation of the plunger 12. This plunger 60 is reciprocably mounted within the upper interior wall of the drum 2, is reduced as at 13' upon the end opposite to that impinged by the finger 11, and about which reduced portion is an expansive helical spring 14 engaging the 65 tapered valve 15, reciprocably mounted within the head 3 of the brake drum.

The valve 15 is for the control of the passageways 16, one upon either side thereof, and lead to the chambers upon the opposite sides 70 of the division wall 17 in the head 3, said chambers being designated by the numerals 18 and 19 and being substantially semi-circular in shape, they being recessed into the annular tapered extension 20 of the face of the 75 head 3.

The major portion of the head 3 is hollow, forming a chamber 21 therein to provide a reservoir for oil and to which communication is established through suitable ball controlled 80 check valves or ports indicated at 22, there being shown three of these communicating with each chamber 18 and 19, which permit oil passing from the chamber 21 into the chambers 18 and 19, as indicated in Figure 1 85 and in which view one of the valves and one of the ports 18 or 19 are shown directly beneath the shaft instead of to one side thereof, for better comprehension.

Within the rotor 5 are carried two series of 90 reciprocable pistons, the larger ones being indicated at 23 and the smaller ones at 24, they being of any relative size desired, but made as numerous as possible for accomplishing smooth and continuous action of the device. 95 Each of these pistons are hollow, open upon their innermost ends and concave upon their outer closed end for engagement with the disc 8 of the thrust bearing. Within the hollow portion of each piston is an expansive helical 100

spring 25 for the purpose of normally holding the pistons in their extreme extended position, the stationary end of each spring impinging against the bottom of the cylinder in which the piston is mounted. The bottom wall of each cylinder is provided with a suitable number of ports or holes 26 so that free communication at all time exists between the cylinders and either one or the other of the chambers 18 and 19 when thereover. As the shaft rotates carrying with it the runner 5, the pistons will revolve the same, and if the rocker head 6 is in neutral position will impart no pumping action whatever in respect to the transfer of oil. However upon motion of the rocker head towards the position indicated in Figure 1 of the drawings the reciprocation of the pistons as they are carried about with the shaft will take place and while passing one of the chambers 18 or 19, depending upon the direction of rotation of the shaft, as is obvious will suck oil from one of the chambers and discharge into the other, and, provided the rocker head has not been thrust to its extreme innermost position as shown in Figure 1 of the drawings, transfer of oil will take place through the passageway 16 from one of the chambers 18 or 19 to the other, but on a full throw of the rocker head 6 which will completely close the valve 15, no such transfer will take place and the braking mechanism become locked or fixed.

By the construction of the valve 15 it will be seen that as long as not held tightly closed by the plunger 12 any pressure of oil through the passageway 16 will tend to slightly unseat same and permit of transfer of the oil through the passageway, the action of the valve being further delicately controlled by the spring 14 which may be of any desired tension, and that a constant supply of oil is maintained in the chambers 18 and 19 through the check valves 22 from the chamber 21.

The control of the rocker head 6 may be governed in any desired manner as for example a crank arm or lever fixed to one of the gudgeons 13 such lever being indicated at 27 and attached to any desired form of operating mechanism.

There is shown upon the opposite ends of the installation suitable ball bearings indicated at 28 and 29 to reduce to a minimum the friction upon the shaft 1.

Having thus described my invention, what I claim and desire to secure by Letters Patent, is:

1. The combination with a shaft, of a housing thereupon, a pump runner within the housing and keyed to the shaft, a plurality of reciprocable pistons within the runner and parallel with the shaft, means for governing the reciprocation of the pistons during their revolutions with the shaft, an oil supply within the housing for the cylinders of the pistons, a selectively controlled bypass intermediate

of the intaking and discharging cylinders whereby braking may be applied to the shaft.

2. The combination with a shaft having a housing mounted thereupon, of a pump runner fixed to the shaft within the housing, a plurality of cylinders having reciprocable pistons therein formed within the runner, an oil supply for said cylinders, a selectively controlled bypass intermediate of the intaking and discharging cylinders whereby compression of oil in the latter imparts braking power to the shaft.

In testimony whereof I affix my signature.

JULIUS PAUL.
